UNITED STATES PATENT OFFICE

ALFRED MARCHEV, OF CHICAGO, ILLINOIS, ASSIGNOR TO TEMPLE, INC., OF CHICAGO,
ILLINOIS, A CORPORATION OF ILLINOIS

STAND

Application filed October 13, 1927. Serial No. 225,975.

My invention relates broadly to stands for supporting articles and more particularly to stands for supporting loud speakers or amplifying horns.

5 The invention has among its objects the production of devices of the kind described that are neat and attractive in appearance, convenient, durable and satisfactory for use wherever found applicable.

10 A particular object of the invention is to provide an improved stand for supporting an article which is substantially cylindrical in form.

Another particular object of the invention 15 is to provide an improved stand for supporting a loud speaker or an amplifying horn in such manner that the loud speaker or amplifying horn may be quickly removed therefrom or assembled therewith.

20 Still another particular object of the invention is to provide an improved stand adapted to support a loud speaker and adapted to hold it in place thereon without being secured to the loud speaker by means 25 of screws, or the equivalent.

Many other objects and advantages of the construction herein shown and described will be obvious to those skilled in the art from the disclosure herein given.

30 To this end my invention consists in the novel construction, arrangement and combination of parts herein shown and described, and more particularly pointed out in the claim.

35 In the drawing, wherein like reference characters indicate like or corresponding parts:

Fig. 1 is a front elevation of a stand embodying the invention, the stand being shown 40 in connection with a loud speaker or amplifying horn;

Fig. 2 is a bottom plan view of the apparatus shown in Fig. 1; and

Fig. 3 is a side elevation of the apparatus 45 shown in Fig. 1.

In the drawing, the improved stand is designated generally by the reference character 10 and it is shown in connection with a loud speaker 11 which is more fully shown 50 and described in the copending application of

Fred W. Temple, Serial No. 209,730, filed August 1, 1927. However, it is to be understood that I make no claim to the details of construction of the speaker 11 and that I am limited to the use of a loud speaker of this 55 description only to the extent indicated in the appended claim.

As shown, the loud speaker 11 is substantially cylindrical in form, its front and rear surfaces 12 and 13, respectively, being more 60 or less convex and its cylindrical surfaces being preferably provided with relatively shallow grooves 14 and 15 adjacent the ends thereof. The bottom surfaces of the grooves 14 and 15 are, in this instance, continuations 65 of the cylindrical surface of the loud speaker and the grooves are formed by providing annular beads 16 and 17 upon the cylindrical surface, the beads 16 being formed at the ends 70 of the cylindrical surface and the beads 17 being formed intermediate the ends of the cylindrical surface. Of course, the beads provide annular shoulders upon the speaker.

The improved stand may be of any suitable size and shape and may be constructed of any 75 suitable material but it preferably has a base which comprises a pair of bent metallic straps or bars 20 and 21 upon which feet 23 are formed. Intermediate their ends, the straps or bars 20 and 21 are preferably provided 80 with substantially arcuate portions 25 and 26, respectively, adapted to engage the grooves 14 and 15, respectively. In the illustrated embodiment of the invention, the curvature of the portions 25 and 26 does not correspond to the curvature of the cylindrical wall of the loud speaker 11 but it is readily understood that in some instances, I may prefer to have the portions 25 and 26 conform 85 to the cylindrical surface of the loud speaker. 90 Riveted to each of the straps or bars 20 and 21 are a pair of more or less resilient members 28. The resilient members 28 may be of any suitable construction but are preferably formed from metallic straps or bars and 95 are preferably constructed so that they function as leaf springs. Thus, as best shown in Fig. 1, the upper end of each member 28 is adapted to rest in the groove 14 or in the groove 15 of the loud speaker 11 and is adapt- 100

ed to engage the cylindrical surface thereof. The points in which the members engage the cylindrical surface of the loud speaker are preferably above a horizontal plane coincident with the longitudinal axis of the loud speaker so that the members 28 yieldingly hold the speaker in place upon the arcuate portions 25 and 26 of the straps or bars 20 and 21. When the loud speaker 11 is lifted from the stand 10, the members 28 assume the positions wherein they are shown in dotted lines in Fig. 1. Then when the loud speaker is returned to the stand, the members 28 are bent into the positions wherein they are shown in full lines in Fig. 1. Therefore, it is readily understood that the members 28 frictionally engage the loud speaker and retain it against accidental displacement relative to the stand. It is also readily understood that the members 28 cooperate with the beads 16 and 17 to prevent longitudinal displacement of the loud speaker relative to the stand.

Means is preferably provided for securing the straps or bars 20 and 21 to each other. Thus, I have shown bars 32 which are riveted to the straps or bars 20 and 21. The feet 23 formed upon the stand 10 are preferably provided with pads 33 of felt, or the equivalent, so that the stand may be positioned upon a varnished surface, or the like, without marring it. I also preferably provide pads 34 of felt, or the equivalent, upon the free ends of the members 28 so that these members will not scratch or otherwise injure the finish upon the loud speaker.

My improved stand is particularly advantageous in that it is not necessary to employ screws, or the equivalent, to fasten the loud speaker to the stand; therefore, the loud speaker and stand may be quickly and easily assembled. Another advantage is that the stands may be packed separately from the loud speakers when a large shipment thereof is to be made.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

A stand for holding an object, said stand comprising spaced straps upon which said object rests, the outer ends of said straps being bent downwardly to provide feet, means rigidly connecting the straps to each other, a pair of resilient members rigidly secured to each of said straps and engageable with said object to secure said straps thereto.

In testimony whereof, I have hereunto signed my name.
